GEORGE P. YORK AND WILLIAM H. WILSON, OF WESTFIELD, NEW YORK.

Letters Patent No. 78,909, dated June 16, 1868.

IMPROVEMENT IN MACHINES FOR GRINDING THE CUTTERS OF MOWING-MACHINES.

The Schedule referred to in these Letters Patent and making part of the same.

TO ALL WHOM IT MAY CONCERN:

Be it known that we, GEORGE P. YORK and WILLIAM H. WILSON, of Westfield, in the county of Chautauqua, and State of New York, have invented a new and useful Improvement in Machines for Grinding the Cutters of Mowing-Machines; and we do hereby declare that the following is a full, clear, and exact description thereof, which will enable others skilled in the art to make and use the same, reference being had to the accompanying drawings forming part of this specification, in which—

Figure 1 represents a front elevation of our improved machine, with a part broken away.

Figure 2 represents a plan view of the same.

Similar letters of reference indicate corresponding parts.

The object of this invention is to provide a simple and cheap machine, whereon the cutter-bars of mowing or reaping-machines may be readily adjusted and held in adjustable guides and supports, to be accurately presented to the grinding-wheel, for grinding the same, no matter of what pattern or angle they may be.

To this end our invention consists in the arrangement, upon a suitable bench, adapted to hold a cutter-bar, of a grindstone, provided with mechanism for communicating a lateral motion of the same to and from the cutter-bar, and of a table, also provided with means for moving to or from the stone; also, in an arrangement of posts and gauges, whereby the cutters are presented to the stone at the proper angle; also, in the combination, with the said posts, of gauges, whereby the proper position of the cutter, with relation to the stone, is determined; also, in an improvement in the construction of the said posts and gauges.

In the drawings, A represents the frame, provided with a table, B, and suitable bearings, for the support of the shaft C of the stone, D, which is arranged to slide lengthwise thereon.

E represents a collar, made fast to the said shaft, between which, and the inner bearing of the shaft, a suitable spring, F, is arranged to bear against the said collar, the tendency of which is to constantly bear the shaft in the direction of the crank.

G represents a loose collar, arranged on the shaft, on the opposite side of the collar E, which is connected, through the bell-crank H, with the treadle I, whereby the shaft may be moved in the opposite direction.

The table B may also be fixed upon ways, as shown at K, and in like manner connected with a treadle or any other suitable means for moving it to and from the stone, and both may be moved together, or either separately, as desired.

L and L' represent posts, secured to the table by bolts L², in a manner to be adjusted to or from the side of the stone, and axially on the said bolts. The upper extension of the said posts is suitably inclined towards the face of the stone, and provided with wood or soft-metal facings, M, to prevent injury to the edges of the cutters, which are liable to be inadvertently exposed to contact with them.

Near the top of the upright portion of the posts are adjustably fixed thereto the gauges M, which are also provided with wood or soft-metal facings M², which are intended, by action upon the edge of the cutters, to determine the lengthwise movement of the cutter-bar.

N and N' represent guides, which are also secured adjustably to the table, which are intended to hold the cutter-bar at the proper angle, with reference to the face of the stone, to permit the latter to bear fair upon the bevelled edges of the cutters when in position to be ground, and through which the cutter-bar may slide to bring the edges of the several cutters to the position to be acted on by the stone.

To grind the cutters of a mowing-machine, the cutter-bar is placed in the guides N, between the post L and the stone, with the points of the cutters upward. The guides N are then adjusted to hold the cutter-bar, so that when the cutters stand at about the same angle vertically, as the face of the upright part of the post L, one edge of the cutters will stand in vertical planes parallel with the grinding-face of the stone. The post L is then adjusted to agree with the cutter-bar, as clearly shown in fig. 1. In this position the cutter-bar is maintained by the hand, until, by the action of the foot on the treadle, the stone is moved up to the edge of the cutter, the latter having been adjusted to the proper position lengthwise of the bar, as determined by the gauge M¹, the

face of which is bevelled, to agree with the edge of the cutters, when the grinding may be proceeded with. When the cutter has been sufficiently ground, and the foot removed from the treadle, the stone will be removed from contact with the same, and out of the way of the movement of the cutter-bar, in a lengthwise direction, which is done to bring the corresponding edge of the next cutter into position to be ground, and the same operation may be continued till all the cutters are ground on the same edge. The cutter-bar is then removed from the guides N N, to those marked N' N', which bear the same relation to the stone on the other side of the axis, and whereby the other edges of the cutters may, in like manner, be ground, as will be readily understood.

After the gauges and posts have been adjusted, they do not require to be changed, so long as cutters of the same pattern are to be ground.

Having thus described our invention, we claim as new, and desire to secure by Letters Patent—

1. The combination, with a table provided with means for holding a cutter-bar, as described, of a grinding-wheel, arranged to slide laterally, substantially as and for the purpose described.
2. The combination, with the posts L and L', of the gauges M', substantially as and for the purpose described.
3. The combination, with cutter-grinding apparatus, of the posts and gauges, provided with the facings of wood or other soft material, substantially as and for the purpose described.
4. The combination, with a grinding-stone provided with means for effecting a lateral movement thereof, of the guides and posts, substantially as and for the purpose described.

GEO. P. YORK,
WM. H. WILSON.
